This invention relates to rotary fluid-flow machines.

According to this invention, a rotary fluid-flow machine includes a turbine and compressor, the rotors of which are integrally formed as a single rotatable member, having two separate sets of flow-defining vanes, or the like, the first set being turbine vanes and the second set being compressor vanes, the casing of the machine in which the member is rotatable being so shaped as to provide an entry to the first set of vanes and also to provide a further entry to the second set of vanes, and the casing being shaped also to provide channels in registry with the exits of both sets of vanes such that the fluids discharged by the compressor and the turbine are mixed together before discharge from the machine through a mixed fluid outlet.

The rotatable member may be of centrifugal type and the casing of scroll or annular type, the latter having a central entry to the compressor. The inlet to the turbine and the mixed fluid outlet may be each spaced apart on opposite sides of the central entry.

The fluid compressed by the compressor may be air, while the fluid driving the turbine may be exhaust gases derived from the exhaust manifold of an associated internal combustion engine.

The fluid flow through the compressor may be generally radially-outwardly, while the fluid flow through the turbine may be generally radially inwardly.

It may be so arranged that the delivery from the compressor passes around the outside of an inner portion of the casing through which the exhaust gases leaving the turbine rotor pass, so that an insulating air envelope is provided around that portion of the casing.

One embodiment of the invention will now be particularly described by way of example with reference to the accompanying drawing which shows in cross-section a rotary fluid-flow machine in the form of a turbine-compressor unit.

Referring to the drawing, the turbine-compressor unit comprises a scroll-type casing 11 formed in two parts 12 and 13. The part 13 of the casing is extended to the right in the drawing to form a sump 14 and to house ball bearings 15 and 16 for rotatably supporting a shaft 17 which projects to the left in the drawing into the part 12 of the casing.

The part 12 of the casing has a central entry 18 to the eye of a single rotatable member 19 mounted upon the left-hand end portion of the shaft 17.

The single rotatable member 19 constitutes an integral compressor and turbine rotor of centrifugal type having an inner set of vanes 20 which are the compressor vanes which register with the central entry 18, and having also an outer set of vanes 21, which are the turbine vanes, and which register on their inlet side with a ring of stator blades 22.

The casing 12 is provided with an inlet 23 through which exhaust gases from the exhaust manifold of an associated internal combustion engine (not shown), can pass into the turbine section of the turbine-compressor unit.

The parts 12 and 13 of the casing 11, together form an outer annular casing, but within it there is provided an inner annular casing 24, the inlet 23 being connected to the interior of the casing 24 by connecting means 25.

2

The part 12 of the casing 11 is also provided with a mixed gas outlet 26, both the exhaust inlet 23 and the outlet 26 being spaced apart on opposite sides of the central entry 18.

5 The outlet side of the compressor portion 20 of the single rotatable member 19 opens into an envelope chamber 27 formed between the inner annular casing 24 and the adjacent wall of the part 13 of the casing 11.

A labyrinth seal 28 is provided to the left of the ball bearing 15 between the shaft 17 and an insert 29 secured to the part 13 of the casing 11. The insert 29 carries a ring of substantially radial stator blades 29a which are positioned on the outlet side of the compressor. A further labyrinth seal 30 is provided between the rotatable member 19 and the part 12 of the casing 11, this seal surrounding the central inlet 18. Another labyrinth seal 31, for gas sealing, is provided in the region between the stator blades 22 and 29a.

In operation of the turbine-compressor unit, exhaust 20 gases from the associated internal combustion engine pass through the exhaust inlet 23 and the connecting means 25 into the interior of the casing 24. The gases then pass through the stator blades 22 and through the vanes 21 of the turbine portion of the rotatable member 19, the resultant expansion through the turbine effecting rotation of this member. The exhaust gases discharging from the turbine pass through the annular chamber 32 formed between the casing 24 and the wall of the casing parts 12 and 13.

30 With rotation of the rotatable member 19 the compressor portion, formed by the vanes 20, draws in air from the surrounding atmosphere through the central inlet 18, compressing this air and discharging it radially-outwardly through the stator blades 29a into the envelope chamber 27. This air, in so passing around the outside of the casing 24, has an insulating effect between the casing 24 and the outer casing components before passing into the chamber 32. The arrangement is such that the exhaust gases discharging from the turbine and the compressed air delivered by the compressor through the envelope chamber 27 mix together efficiently in the annular chamber 32 before passing from the unit through the mixed outlet 26.

The casing parts 12 and 13 are connectible together in 45 a number of relative rotational positions to afford adjustment of the positioning of the inlet 23 and the outlet 26 in relation to the sump 14.

Further, conventional waste-gate means (not shown) 50 may be incorporated in the turbine-compressor unit in conjunction with the connecting means 25 to permit some of the exhaust gases to by-pass the turbine when so necessary.

Such a turbine-compressor unit may with advantage be employed in the exhaust system of an internal combustion 55 engine for introducing additional air into the exhaust gases upstream of a device for reducing the toxic element content of the exhaust gases passing to atmosphere.

Alternatively, the turbine-compressor unit may be utilised for desired and efficient mixing of any two fluids, 60 where one of the fluids can be supplied under pressure so as to provide the driving energy for the turbine section of the unit.

By providing the turbine and compressor rotors in the 65 form of a single rotatable member, considerable simplicity in the design of the casing in which the member is rotatably mounted, is achieved.

70 Although in the embodiment described the compressor in generally of the radial-outward flow type and the turbine generally of the radial-inward-flow type, in alternative embodiments of the invention, by suitable modification of the rotor and casing, other flow directions for both turbine and compressor fluid can be accommodated.

We claim as our invention:

1. A rotary fluid-flow machine including a turbine and compressor, the rotors of which are integrally formed as a single rotatable member of wholly centrifugal type having two separate sets of flow-defining vanes, the first set being turbine vanes and the second set being compressor vanes, the casing of the machine in which the member is rotatable being so shaped as to provide an entry to the first set of vanes and also to provide a further entry to the second set of vanes, and the casing being shaped also to provide two separate channels respectively in registry with the exits of the sets of vanes, said separate channels so opening into each other that the fluids discharged by the compressor and the turbine are mixed together downstream of the turbine vanes but before discharge from the machine through a mixed fluid outlet, the said casing having an inner portion through the interior of which the exhaust gases leaving the turbine pass, and around the outside of which the fluid delivered by the compressor passes, so that an insulating air envelope is provided around that portion of the casing.

2. A rotary fluid-flow machine as claimed in claim 1, wherein the casing is formed in two parts, one of which

forms a sump for the machine and houses bearings for supporting the single rotatable member, while the other part includes the entries and the outlet of the machine.

3. A rotary fluid-flow machine as claimed in claim 1, wherein the casing parts are connectible together in a number of relative rotational positions to afford adjustment of the positioning of the inlet to the turbine and of the mixed fluid outlet in relation to the sump.
